DESIGN FOR A FOUNTAIN TOOTHBRUSH

John D. Kells, Brooklyn, N. Y.

Application July 11, 1941, Serial No. 102,031

Term of patent 14 years

To all whom it may concern:

Be it known that I, John D. Kells, a citizen of the United States, residing at Brooklyn, in the county of Kings and State of New York, have invented a new, original, and ornamental Design for a Fountain Toothbrush, of which the following is a specification, reference being made to the accompanying drawing, forming a part thereof, in which

Figure 1 is an elevational view of a fountain toothbrush showing my new design.

Figure 2 is a side elevational view thereof with the cover cap removed.

Figure 3 is a bottom plan view of the fountain toothbrush shown in Figure 2.

Figure 4 is a cross-sectional view thereof taken on line 4—4 of Figure 2.

I claim:

The ornamental design for a fountain toothbrush, as shown.

JOHN D. KELLS.
